BENJAMIN C. WEBSTER, OF BRIDGEPORT, CONNECTICUT, ASSIGNOR TO HARVEY HUBBELL, INCORPORATED, OF BRIDGEPORT, CONNECTICUT, A CORPORATION OF CONNECTICUT

KEY-SOCKET.

1,178,561.

Specification of Letters Patent. Patented Apr. 11, 1916.

Application filed September 8, 1914. Serial No. 860,763.

To all whom it may concern:

Be it known that I, BENJAMIN C. WEBSTER, a citizen of the United States, residing at Bridgeport, county of Fairfield, State of Connecticut, have invented an Improvement in Key-Sockets, of which the following is a specification.

This invention relates more especially to key sockets and snap switches and has for its object to provide a simple and inexpensive reversible escapement switch movement which shall be wholly inclosed in the insulating blocks and so shaped as to avoid weakening the blocks, which shall be easy to assemble, thereby dispensing with skilled labor, which will give a greater break than ordinary switches of this type, will both make and break quickly and will carry double the load of an ordinary socket switch. With these and other objects in view I have devised the novel mechanism which I will now describe, referring to the accompanying drawing forming a part of this specification and using reference characters to indicate the several parts.

Figure 1 is a view partly in elevation and partly in section, showing my novel switch mechanism as applied to a key socket; Fig. 2 a plan view of the lower insulating block and the parts carried thereby, the terminals being in section; Fig. 3 a section on the line 3-3 in Fig. 2, looking in the direction of the arrows; Fig. 4 a section on the line indicated by 4 in Fig. 2, looking in the direction of the arrow; Fig. 5 a section of the escapement bracket on the line indicated by 5 in Fig. 12, looking in the direction of the arrow; Fig. 6 a perspective of the contact member detached; Figs. 7 and 8 are views of the tripping slide detached; Figs. 9 and 10 views of the actuating member detached; Fig. 11 an enlarged sectional view on the line 11-11 in Fig. 12, looking in the direction of the arrows; Fig. 12 a sectional view on the line 12-12 in Fig. 11, looking in the direction of the arrows; and Fig. 13 is a view on an enlarged scale corresponding with Fig. 5, and showing two full line and three dotted positions of the tripping lug. 20 denotes the upper insulating block and 21 the lower insulating block by which the operative parts are carried, said blocks being provided with recesses which receive the parts leaving them wholly inclosed.

22 denotes a U-shaped escapement bracket 55 in which the shaft 23 is mounted to rotate. The inner face of one of the arms of the bracket is provided with sector lugs, indicated by 24, said lugs being adapted to be engaged by a lug 25 on a tripping slide 60 26 which is also provided with an arm 27, as will be more fully explained. The tripping slide lies in ways 28 in a contact member 29 which is adapted to turn freely on the shaft. The contact member is provided with 65 contact arms 30 and 31, the latter being U-shaped to furnish an additional bearing on the shaft and provided with side wings 32.

33 denotes the actuating member which 70 is carried by the shaft and is provided with engaging walls 34 and an engaging arm 35.

36 denotes a spring coiled about the shaft and having arms 37 which are engaged by arm 35, and engage arm 27 of the tripping 75 slide and the side wings 32 of the contact member. This spring actuates the contact member and returns the slide after each operation.

38 and 39 denote the terminals. It of 80 course makes no difference which way the current passes. Suppose, for example, that the current enters terminal 38 and passes through screw 40 to the screw shell, indicated by 41, thence through the lamp from 85 which it passes to center contact 42, which has formed integral therewith a plate 43 from which a contact spring 44 extends into position to be engaged by arm 30 of the contact member. From the contact member, 90 the current passes to a contact spring 45 extending from a plate 49 which engages terminal 39.

The operation is as follows: Rotation of the shaft in either direction carries the actuating member with it. The engaging arm 35 of this member carries one arm of the spring with it, for example, as shown in Fig. 11 (in which the movement of the shaft is clockwise), which winds the spring, the 100 other arm thereof being held stationary by contact arm 31 (the bearing as shown is on the wing pieces of said arm) of the contact member. This movement continues until one of the engaging walls 34 of the actuating member engages arm 27 of the tripping slide. This will move the tripping slide from the position shown in Figs. 11 and 12.

toward the position indicated by dotted lines in Fig. 12 and will move lug 25 from its normal position between two of the sector lugs on the escapement bracket, said position being the central dotted position in Fig. 13. The dotted position of said lug in Fig. 12 is at the instant before said lug is disengaged from the sector lug when moving clockwise.

13 It will be noted (see Fig. 13) that lug 25 although sector shaped is non-concentric with the sector lugs on the escapement bracket and is provided with engaging corners 46 and 48. The instant engaging corner 46 clears the corner of the sector lug in the clockwise direction, the entire power of the wound spring will be exerted upon contact arm 31 of the contact member to give said member a quick quarter turn. The instant this quarter turn of the contact member is effected the operative arm of the spring, acting on arm 27 of the tripping slide, will return said slide to its normal position and draw lug 25 between sector lugs 24 on the escapement bracket (see dotted position at the left in Fig. 13) and both arms of the spring will resume their normal position with relation to engaging arm 35 and arm 31 of the contact member, which 30 position will be a quarter turn clockwise from the position shown in Fig. 11. The contact member is stopped at the end of each quarter rotation by the engagement of corner 46 on lug 25 with the next sector lug. 35 Owing to the non-concentric position of lug 25 on the tripping slide relatively to the sector lugs, the passing of lug 25 over a recess between sector lugs is made impossible as the inner wall of lug 25, when the engaging 40 corner passes the forward corner of the sector lug, is retained in close engagement therewith through the action of the spring on engaging arm 35 of the actuating member which in turn, through engaging wall 45 34, acts on arm 27 of the tripping slide, and the lug is drawn inward slightly so that it must engage the end wall of the next sector lug. The instant the lug 25 clears the sector lug with which it has engaged it will be 50 drawn inward between that sector lug and the one next in advance, as in the dotted position at the left in Fig. 13. The contact members is retained out of engagement with the faces of the sector lugs by a spacing 55 washer 47 interposed between the escapement bracket and the contact member. Suppose that the parts were in the circuit closing position; that is, with arms 30 and 31 in engagement with contact springs 44 and 45, 60 respectively. The movement just described would open the circuit, a second quarter turn of the shaft would close the circuit, a third quarter turn of the shaft would open the circuit again and a fourth quarter turn 65 of the shaft would close it again, leaving the

parts in the starting position. Suppose now that the shaft is rotated in the opposite direction. The operation will be the same with the exception that lug 25 on the tripping slide will be moved inward toward the inner full line position in Fig. 13 instead of outward as before. When the tripping slide is moved inward, the corner of said lug, indicated by 48, becomes the engaging corner. The tripping slide is moved inward by the actuating wall 34 on the actuating member that was inoperative before. As soon as lug 25 passes the sector lug on the escapement bracket in counter clockwise direction, the action of the spring will be to force the tripping lug outward instead of to draw it inward as before. Engaging corner 48 will now ride along the inner wall of the sector lug and as soon as it passes the farther inner corner of said lug it will be slightly forced outward and slightly into the recess between the sector lugs and will engage the second sector lug in counter clockwise direction, as indicated by the dotted position of said lug at the right in Fig. 13, these movements being continued to open and close the circuit as before.

Having thus described my invention I claim:

1. In a switch for lamp sockets, a mechanism comprising an actuating member having an engaging arm and engaging walls, an escapement bracket having sector lugs, a rotatable contact member having contact arms, a tripping slide carried by the contact member and having a lug adapted to engage the sector lugs and an arm, and a spring having arms adapted to be engaged by the opposite sides of the engaging arm and to engage the opposite sides of the arm of the tripping slide and the opposite sides of a contact arm, whereby rotation of the actuating member will wind the spring, will actuate the slide and disengage the lug thereon from the sector lugs, will impart a quarter rotation to the contact member to open or close the circuit and will then return the slide and engage the lug thereon with the sector lugs.

2. In a switch for lamp sockets, a mechanism comprising a bracket having sector lugs, a rotatable contact member having contact arms, a tripping slide carried by the contact member and having an arm and a lug adapted to engage the sector lugs, an actuating member having an engaging arm and engaging walls, said engaging arm, the arm of the tripping slide, and one of the contact arms being normally in alignment, and a spring having arms engaging both sides of the before-mentioned arms, whereby rotation of the actuating member will cause the engaging arm to wind the spring and one of the engaging walls to actuate the tripping slide to release the contact mem-

ber and open or close the circuit, after which the parts are returned to normal position by the spring.

3. In a switch for lamp sockets, a mechanism comprising a bracket having sector lugs, a rotatable contact member having contact arms, a tripping slide carried by the contact member and having an arm and a lug non-concentric with the sector lugs, and
- 10 provided with engaging corners adapted to engage either the inner or outer walls of the sector lugs, an actuating member having an engaging arm and engaging walls, said engaging arm, the arm of the tripping slide, and one of the contact arms being nor-

mally in alinement, and a spring having arms engaging both sides of the before-mentioned arms, whereby rotation of the actuating member will cause the engaging arm to wind the spring and one of the engaging walls to actuate the tripping slide to release the contact member and open or close the circuit, after which the parts are returned to normal position by the spring.

In testimony whereof I affix my signature 25
in presence of two witnesses.
